UNITED STATES PATENT OFFICE.

JOHN HARRIS, OF CLEVELAND, OHIO.

BLOWPIPE.

Application filed January 27, 1923. Serial No. 615,193.

To all whom it may concern:

Be it known that I, JOHN HARRIS, a citizen of the United States, residing at Cleveland, in the county of Cuyahoga and State of Ohio, have invented a certain new and useful Improvement in Blowpipes, of which the following is a full, clear, and exact description, reference being had to the accompanying drawings.

10 This invention relates to blowpipes, and has for its general object to provide improved parts and connections whereby the supplying of gases to the blowpipe head through and in connection with the handle and the valve-block may be improved.

Further and more limited objects of the invention are to provide an improved connection between the individual pipes and the front portion of the handle casing; to provide improved means for controlling the supply of the cutting oxygen to the blowpipe; and to improve the construction and operation of the valve which controls such oxygen supply.

25 Still further and more limited objects of the invention will appear hereinafter and will be set forth in the claims appended hereto.

In the drawings forming part hereof, Fig. 1 represents a side elevation of a blowpipe and its handle portion, embodying my invention;

30 Fig. 2, a plan view of the rear portion of the blowpipe assembly shown in Fig. 1;

35 Fig. 3, a detail in sectional elevation through the handle portion of the blowpipe;

40 Figs. 4 and 5, sectional details taken respectively on the lines 4—4 of Fig. 1 and 5—5 of Fig. 4;

Fig. 6, a like detail taken on the line 6—6 of Fig. 4;

Fig. 7, a sectional detail taken on the line 7—7 of Fig. 3;

45 Fig. 8, a sectional detail taken on the line 8—8 of Fig. 1;

Fig. 9, a sectional detail taken on the line 9—9 of Fig. 4; and

50 Fig. 10, a sectional detail taken on the line 10—10 of Fig. 9.

Describing the various parts by reference characters, 1 denotes generally a blowpipe head, the same being of any construction adapted to cut metal with oxygen in the usual manner and adapted to have connected thereto the tubes 2, 3 and 4, which conduct

to such head cutting oxygen, preheating oxygen, and a combustible gas, respectively.

These tubes extend rearwardly from the blowpipe head and are connected at their rear ends to a valve block, which block will now be described. This valve block comprises an intermediate cylindrical portion 5 and a forwardly projecting portion 6 of smaller sectional area than the portion 5. The portion 5 receives the cylindrical rear end of a handle casing 7, which casing is fastened thereto in any suitable manner, as by means of screws 8. The rear end of the valve block projects beyond the handle casing 7, as indicated at 9, there being an annular shoulder 9^a between the parts 5 and 9 against which the rear end of the handle casing may abut.

Integral with the rear end of the valve block are connections 10 and 11, the former connection being adapted to receive oxygen and the latter connection any suitable combustible gas, the gases being supplied thereto from tanks or containers in the usual manner through flexible tubing (not shown) applied to the detachable connection-extensions 10^a and 11^a.

Combustible gas supplied through the connection 11 enters the valve block through the L-shaped passageway 12, the vertical branch of said passageway being adapted to discharge into the valve chamber 13, from which a passageway 14 leads to a connecting socket 15 in the portion 6 of the valve block, said socket having the pipe 4 connected thereto; a needle valve 16 mounted in the rear portion 9 of the valve block controls the flow of combustible gas from the passage 12 through the passage 14 to the pipe 4.

Oxygen for cutting purposes and for admixture with the combustible gas is supplied to the connection 10 and thence, by passageways 17 and 18, to the valve chambers 19 and 20, respectively. The first-mentioned valve chamber has therein a needle valve 21 adapted to control the upper part of the passageway 17, and from said chamber a passageway 22 leads to the socket connection 23 in the portion 6 of the valve block, which socket connection receives the rear end of the pipe 3.

The valve chamber 20 extends longitudinally of the valve block and has its rear end provided with a thread 20^a in which is threaded the removable cap 24. The for-

ward end of the chamber 20 is provided with a central annular valve seat 25 from which a passageway 26 extends forwardly, said passageway being connected by a vertical passageway 27 with a passageway 28 in the front end of the block and communicating with the socket 29 in which the rear end of the pipe 2 is mounted. The pipes 2 and 3 are crossed within the handle, as shown in Fig. 3, so that the pipe 2 will be uppermost and pipe 3 the middle pipe of the series connecting with the blowpipe head—the particular type of blowpipe illustrated herein being adapted for the supply of cutting oxygen to the top of the head thereof and for the supply of preheated oxygen to a suitable passageway located below the one for cutting-oxygen.

The forwardly extending central portion 6 of the valve block has reciprocably mounted therein a valve-operating stem, the rear end of said stem operating the valve that controls the flow of cutting oxygen through the pipe 2. This valve comprises a body 30, preferably of brass, the body having an intermediate reduced cylindrical portion and hexagonal, or other polygonal end portions 30^a, adapted to engage the cylindrical inner wall of the chamber 20 and to provide for the free flow of oxygen through the segmental passages 31 provided around such cylindrical and angular portions (see Figs. 4 and 9). The front end of the valve 30 is provided with a forwardly projecting annular flange 32 and with a central stud 33. Mounted within the flange and surrounding the stem is an annular rubber seat 34, which is clamped in place by spinning the upper portion of the flange 32 inwardly.

40 The rubber seat 34 is adapted to contact with the rearwardly projecting annular valve seat 25, and the central stud 33 is adapted to be engaged by the rear end 35^a of the valve-operating stem 35. The rear portion of this stem is reduced, the front portion of said stem being enlarged and fitting within a guideway 36 provided in front of the passage or chamber 26 and extending through a plug 37 which is threaded into an enlarged recess in the front end of the valve-block portion 6.

55 In order to provide an efficient packing for the stem 35 which will prevent the escape of oxygen therearound, rubber diaphragms 38 are clamped between the rear of the plug 6 and the seat formed for the rear end of such plug in the front of the part 6, said diaphragms fitting closely about the stem 35 and, as the latter is moved rearwardly to open the valve 30, being bulged rearwardly by such movement into the rear part 39 of the plug chamber, such bulging insuring a close gripping contact between the edges of the bores of said diaphragms and the stem. Furthermore, the pressure of

the oxygen against the diaphragms tend to close their inner walls against the stem.

A spring 40 bears at one end against the rear end of the valve 30 and at its opposite end against the cap 24, within a cup formed therewithin, and normally holds the said valve against the seat 25. For the purpose of operating the valve 30 to permit oxygen to flow through the pipe 2, I provide an angle lever and mount the same upon the 75 casing 7. The casing is provided with a slot 7^a in the top thereof and a pivotal support for the angle lever is formed by means of a sheet metal housing 41 secured to the casing 7 by means of a base flange 41^a riveted to such casing. The upwardly projecting portion of the housing provides a support by its opposed parallel walls 41^b for a pivot 42 on which the angle of the operating lever is mounted. The lever comprises a relatively long operating arm 43 projecting forwardly from the housing 41 and a short valve-operating arm 43^a projecting through the slot 7^a and in operative relation to the forward end of the stem 35. At the front end, the casing is drawn by dies into a shape to provide a resilient clamping portion 7^b, the said end portion being so shaped as to form resilient clamping seats for the reception of the pipes 2, 3 and 4. The top and bottom seats are indicated at 7^c and are so shaped as to engage the major portions of the parts of the pipes 2 and 4 which extend respectively therethrough. The intermediate seats 7^d are also shaped so as to engage considerable portions of the opposite sides of the part of the pipe 3 which passes therethrough, the opposite walls of the parts 7^b being pressed inwardly between the pipe-receiving and engaging portions thereof, as clearly indicated in Fig. 8. The pipe-engaging part of the casing 7 is given the particular shape shown and described prior to the insertion of the pipes 2, 3 and 4 therethrough and into the valve block sockets; and the parts are so shaped that the pipes are gripped tightly by the co-operating parts 7^b.

By the construction shown and described herein, the flow of preheating gases and cutting oxygen to the blowpipe is readily controlled and the supply of cutting oxygen is conveniently effected by use of the hand which grasps the handle 7. The manner of mounting the oxygen valve and the arrangement of the parts for operating the same enables this valve to function most effectively without any leakage of oxygen and without any unsightly projections on the handle casing. When the valve 30 becomes worn, it is very easily removed and a new valve inserted, and the cost of such valve is relatively small. The diaphragms 38 provide a most effective and long-lasting stuffing box for the operating stem 35.

In practice, the pipe engaging portion 7^b of the handle casing is shaped by means of suitable dies into the three clamps that are shown, which clamps engage their respective pipes so firmly that the latter have to be driven through such clamps and into their sockets in the valve block. The clamps thus serve to space the pipes apart and prevent any rattling between the handle 10 casing and the pipes. This freedom from rattling is due to the tight clamping and the resilience of the metal of which such clamping portion is composed.

Having thus described my invention, 15 what I claim is:

1. In a blow pipe, the combination of a head, a valve block, tubes for conducting oxygen and a combustible gas from said valve block to said head, a handle casing 20 mounted on the valve block and extending toward the blow pipe head and having its forward end formed into clamps engaging said tubes, one or more valves in said block, and valve-operating means carried by said 25 casing.

2. In a blow pipe, the combination of a head, tubes for conducting oxygen and a combustible gas to said head, a handle cas-

ing surrounding said tubes and having an end formed into clamps yieldingly engaging 30 the said tubes, a valve for cutting oxygen, and means for operating said valve.

3. In a blow pipe, the combination of a head, a valve block, tubes connecting the said head and valve block for conducting 35 cutting and preheating oxygen and a combustible gas from the block to the head, and a handle casing mounted upon and projecting forwardly from the valve block, the front end of said casing being formed into 40 a pair of opposed resilient walls each having seats formed therein for said tubes and yieldingly engaging the latter.

4. In a blow pipe, the combination of a head, a valve block having connections for supplying cutting and preheating oxygen and a combustible gas to said head, tubes connecting the said head and the said valve block, and a handle casing secured to and projecting forwardly from said block and 50 having its front end formed into resilient clamping means engaging and supporting the said tubes.

In testimony whereof, I hereunto affix my signature.

JOHN HARRIS.
